CLAIM

The ornamental design for a ceiling fan motor housing and light kit combination, as shown and described.

DESCRIPTION

[FIG. 1 is a top perspective view of a ceiling fan motor housing and light kit combination shown in the environment of a ceiling fan, showing our new design;]

[FIG. 2 is a bottom perspective view thereof;]

[FIG. 3 is a top plan view of the motor housing and light kit combination, having the ceiling fan environment removed;]

[FIG. 4 is a bottom plan view thereof;]

[FIG. 5 is a front side view thereof; and,]

[FIG. 6 is a right side view thereof.]

FIG. 7 is a top perspective view of a ceiling fan motor housing and light kit combination shown in the environment of a ceiling fan, showing our new design;

FIG. 8 is a bottom perspective view the ceiling fan motor housing and light kit combination of FIG. 7;

FIG. 9 is a top plan view of the motor housing and light kit combination of FIG. 7, having the ceiling fan environment removed;

FIG. 10 is a bottom plan view of the motor housing and light kit combination of FIG. 7;

FIG. 11 is a front side view of the motor housing and light kit combination of FIG. 7; and,

FIG. 12 is a right side view of the motor housing and light kit combination of FIG. 7.

(Continued)

Portions of the ceiling fan environment and the ceiling fan motor housing and light kit combination are shown in broken lines. Portions shown in broken lines form no part of the claimed design.

1 Claim, 12 Drawing Sheets

Matter enclosed in heavy brackets [ ] appears in the original patent but forms no part of this reissue; matter printed in italics indicates the additions made by reissue.
